CLAIM

The ornamental design for a hair brush handle, as shown, and described.

DESCRIPTION

FIG. 1 is a perspective view of the hair brush handle;

FIG. 2 is a side view of the hair brush handle;

FIG. 3 is a bottom view of the hair brush handle; and,

FIG. 4 is a top view of the hair brush handle.

The broken lines shown in the drawings depict portions of the hair brush handle that form no part of the claimed design.
